Law p.c.

(57) **CLAIM**

The ornamental design for a light for photography and
video, as shown and described.

DESCRIPTION

FIG. 1 is a perspective view of a light for photography and
video showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of the selected portion 8 in FIG.
1; and,

FIG. 10 is an enlarged view of the selected portion 9 in FIG.
3.

The broken lines shown in the figures depict portions of the
light for photography and video that form no part of the
claimed design.

The additional broken lines encircling the enlarged views in
FIG. 1, 3, 9 and 10 are for annotative purposes only and form
no part of the claim thereof.

1 Claim, 10 Drawing Sheets
